US00D770256S

(12) **United States Design Patent** (10) **Patent No.:** **US D770,256 S**
(45) **Date of Patent:** **** Nov. 1, 2016**

(54) **CLAW HAMMER**

(71) Applicant: **Fiskars Brands, Inc.**, Madison, WI
(US)

(72) Inventors: **Aaron Honadel**, Ixonia, WI (US);
Steven Stokes, Fitchburg, WI (US);
Colin Roberts, Madison, WI (US);
Petteri Masalin, Helsinki (FI); **Sami Lyytikäinen**, Lohja (FI)

(73) Assignee: **Fiskars Brands, Inc.**, Middleton, WI
(US)

(**) Term: **15 Years**

(21) Appl. No.: **29/531,267**

(22) Filed: **Jun. 24, 2015**

(51) LOC (10) Cl. **08-02**

(52) U.S. Cl.

USPC **D8/75**

(57) **CLAIM**

We claim the ornamental design for a claw hammer, as shown and described.

DESCRIPTION

FIG. 1 is a front perspective view from below of the claimed design according to one embodiment;

FIG. 2 is a rear perspective view from below of the claimed design of FIG. 1;

FIG. 3 is a front view of the claimed design of FIG. 1;

FIG. 4 is a left side view of the claimed design of FIG. 1;

FIG. 5 is a rear view of the claimed design of FIG. 1;

FIG. 6 is a right side view of the claimed design of FIG. 1;

FIG. 7 is a top view of the claimed design of FIG. 1;

FIG. 8 is a bottom view of the claimed design of FIG. 1; and,

FIG. 9 is a detail view of a portion of the handle of the claimed design.

Any portion of the article depicted in broken lines forms no part of the claimed design. As shown in FIG. 9, the circular features on the grip of the handle are depicted in broken lines.

1 Claim, 5 Drawing Sheets
